UNITED STATES PATENT OFFICE.

JAMES C. HODGES, OF ATTLEBORO, MASSACHUSETTS, ASSIGNOR TO SIDNEY O. BIGNEY.

ELASTIC TENSION DEVICE.

1,020,553.

Specification of Letters Patent. Patented Mar. 19, 1912.

Application filed August 11, 1911. Serial No. 643,490.

To all whom it may concern:

Be it known that I, JAMES C. HODGES, a citizen of the United States, residing at Attleboro, in the county of Bristol and State 5 of Massachusetts, have invented certain new and useful Improvements in Elastic Tension Devices, of which the following is a specification.

My invention relates to a device intended 10 for introduction into the straps of suspenders, garters, or other supporting means as a substitute for elastic webbing.

The principal objects of my invention are 15 to increase the elastic action and facilitate the movement of the parts; to prevent buckling or cramping of the spring; to prevent any noise or abrasion by reason of the movement of the spring; and to reduce the cost of construction to a minimum.

20 To the above ends essentially my invention consists in such novel parts and combinations of parts as fall within the scope of the appended claims.

In the accompanying drawings which 25 form a part of this specification, Figures 1 and 2, are front elevations of my attachment embodied, respectively, in the strap of a suspender and in the strap of a garter, Fig. 3, a front elevation of the spring carrying member before the spring has been applied thereto, Fig. 4, a like elevation of the same after the spring has been applied thereto and the binding plate mounted thereon, Fig. 5, a detail view of a sleeve, 35 Fig. 6, a section on line $\alpha-\alpha$ of Fig. 4, Fig. 7, a central vertical section of my attachment in contracted position, and Fig. 8, a front elevation of the same in extended position, showing a portion of the casing broken 40 away.

Like reference characters indicate like parts throughout the views.

In the drawings 1 represents the lower end of a shoulder strap, 2 the slotted plate, 45 3 the supporting strap, and 4 the engaging member of a pair of suspenders with which my device is employed, as shown in Fig. 1. In Fig. 2 the corresponding parts 5, 6, 7, and 8, of a garter are shown.

50 My device is thus constructed: A length of wire, preferably half round in transverse section is bent to form a horizontally-disposed oblong loop 10 with the remainder of the wire length consisting of two straight rods 11 contacting along their flat faces

throughout their length to form a single cylindrical post depending midway the length of the loop 10. Slidable on the post 11 adjacent the loop is a plate 12 having a central opening 13 to loosely admit the post. 60 This plate has downwardly extending parallel sides 14 with prongs 15 upon their lower margins. A tube of zinc or other suitable material is cut into short lengths or sleeves 17 and the series placed upon the 65 post 11. These sleeves are of sufficient internal diameter to move loosely on the post. Then a spiral spring 19 having a diameter sufficient to engage the exterior faces of the tubes 17 is placed over the tubes and the post in compressed position. When the spring is released its convolutions separate the tubes 17 upon the post at intervals throughout the length of the expanded spring. The lower portions of the wire constituting the post 11 are outwardly bent in opposite directions forming horizontal arms 20 in the vertical plane of the loop 10. These arms 20 have their ends 21 upwardly curved as at 22. The arms 20 serve as a support for 80 the lower end of the spring 19 and in conjunction with the casing prevent rotation of the post. 5

The spring and post is inclosed in a casing 24 of textile material, preferably non- 85 elastic webbing. The casing is formed by a strip of material having a looped lower end portion passing through a slotted plate 2. The upper ends of the casing material rest against the inner faces of the walls 14 90 of the cap or plate 12 and are engaged by the inturned teeth 15. These parts may be further engaged by rivets or wire 26 or other fastening means. The side margins of the casing as at 28 may be sewed together 95 throughout their length.

It will be understood that the particular construction of the casing is immaterial so long as the operative parts are accommodated therein. Neither is the particular 100 method of connection of the engaging member 4 with the casing 24 material.

It will be noted that upward tension of the strap 1 connected with the loop 10 compresses the spring 19 by pressing the latter 105 against the plate or cap 12 constituting the top of the casing. The spring thus compressed is shown in Fig. 8. When the tension is relieved by a descent of the strap 1 the spring resumes its normal expanded pos- 110.

sition shown in Fig. 7. During the compression and expansion of the spring the sleeves 17 serve to maintain the coils of the spring uncrampled in vertical alinement 5 whereby the spring is not set nor permitted to abrade the inclosed post, nor to produce noise resultant upon a cramping or scraping of the spring. The sleeves move freely and noiselessly on the post, and being inter- 10 spaced allow ample longitudinal movement of the spring while firmly supporting the latter.

What I claim is:—

1. A tension device of the type set forth, 15 comprising a post, an engaging member upon one end of the post, a spiral spring upon the post, means upon the other end of the post for supporting the spring, tubular members slidably mounted upon the post 20 wholly within the spring, and a casing slidably mounted upon the post and engaging the upper end of the spring to compress the same.

2. A tension device of the type set forth, 25 comprising a post, a spiral spring upon the post, means upon the post for supporting the spring, tubular members slidably mounted upon the post within the spring, and a casing slidably mounted upon the 30 post and engaging the upper end of the spring to compress the same.

3. A tension device of the type set forth, comprising a post, an engaging member upon the upper end of the post, a spiral 35 spring upon the post below the engaging member, interspaced tubular members slidably mounted upon the post within the spring, and a casing slidably mounted upon the post and engaging the upper end of the 40 spring to compress the same.

4. A tension device of the type set forth, comprising a post, an engaging member upon one end of the post, means upon the other end of the post for supporting the 45 spring, a spiral spring upon the post, tubular members slidably mounted upon the post and engaging the spring, and a casing slidably mounted upon the post and engaging the upper end of the spring to compress the 50 same.

5. A tension device of the type set forth, comprising a post, an engaging member upon the upper end of the post, a spiral spring upon the post, means upon the post 55 for supporting the spring, interspaced metallic tubular members loosely mounted upon the post and engaging intermediate portions of the spring, and a casing slidably mounted upon the post and engaging the upper end 60 of the spring to compress the same.

6. A tension device of the type set forth, comprising a post, an engaging member upon one end of the post, arms upon the other end of the post, a spiral spring sur- 65 rounding the post and seated upon the arms,

tubular members slidably mounted upon the post, and a casing slidably mounted upon the post and engaging the spring to compress the same.

7. A tension device of the type set forth, 70 comprising a post, an engaging member upon one end of the post, arms upon the other end of the post, a spiral spring surrounding the post and seated upon the arms, slidable means for maintaining the spring 75 out of contact with the post located upon the post within the spring and in contact with the spring, and a casing slidably mounted upon the post and engaging the spring to compress the same.

8. A tension device of the type set forth, comprising a post, an engaging member upon the upper portion of the post, oppositely-disposed arms upon the lower portion of the post provided with inwardly-curved 85 ends, a spring upon the post seated upon the arms, slidable members upon the post within the spring, a casing comprising a housing portion inclosing the spring and arms, and a bearing portion resting upon the end of the 90 spring and provided with an opening to loosely receive the post.

9. A tension device of the type set forth, comprising a post, an engaging member upon the one end of the post, oppositely-disposed arms upon the other end of the post provided with curved ends, a spiral spring 95 upon the post, slidable members mounted upon the post and contacting with the spring, a casing comprising a housing portion inclosing the arms, and a bearing portion abutting against the end of the spring and slidably mounted upon the post.

10. A tension device of the type set forth, comprising a horizontally-disposed loop, a 105 post, and diverging arms formed from a single piece of bendable material, a spiral spring surrounding the post intermediate the loop and arms, slidable members upon the post engaging the spring, and a casing 110 inclosing the post and arms and engaging the end of the spring adjacent the loop said casing being provided with an opening to receive the post.

11. A connection between two strap members comprising a metallic body portion, a spiral spring loosely coiled around said body portion, a plurality of members within the coil of said spring strung upon said body portion at intervals apart from each 115 other and slidable thereon, a slidable member seated upon said spring and adapted to slide on said body portion thereby contracting the spring when the slidable member moves toward one end of said body portion, 125 the other end of said body portion being connected with one of said strap members, said slidable member being connected with the other of said strap members.

12. A connection between two strap mem- 130

bers comprising a metallic body portion, a spiral spring loosely coiled around said body portion, a plurality of members within the coil of said spring strung upon said body portion at intervals apart from each other and slideable thereon, a slideable member seated upon said spring and adapted to slide on said body portion thereby contract-

ing the spring when the slideable member moves toward one end of said body portion. 10
In testimony whereof I have affixed my signature in presence of two witnesses.

JAMES C. HODGES.
